UNITED STATES PATENT OFFICE.

WILLIAM E. McCAIN, OF ERIE, PENNSYLVANIA.

GRADING MACHINE.

1,406,743.

Specification of Letters Patent. Patented Feb. 14, 1922.

Application filed January 12, 1920. Serial No. 350,952.

To all whom it may concern:

Be it known that I, WILLIAM E. McCAIN, a citizen of the United States, residing at Erie, in the county of Erie and State of Pennsylvania, have invented new and useful Improvements in Grading Machines, of which the following is a specification.

This grading machine is so designed as to make available steam shovels as ordinarily constructed. It is designed to give a wide range of operation especially with relation to shallow grading such as is encountered in ordinary road work and in renewing pavements.

15 The invention is illustrated in the accompanying drawing wherein 1 marks the axle, 2 the wheels, 3 the frame, 4 the turn-table or platform rotatively mounted on the frame, 5 the main boom, 6 the dipper stick, 7 the crowding engine mounted on the main boom and operating the pinion 8, 9 a rack on the dipper stick operating on the pinion 8, and 10 a cable extending from the strut 10^a to the main boom and being adjustable through 20 25 a drum 10^b, the cable 10 supporting the main boom. These parts are of ordinary steam shovel construction.

An auxiliary boom 11 preferably in the form of an I-beam is secured to a bracket 12 and the bracket 12 is pivotally mounted on a pin 13 which pin preferably also forms a pivotal mounting for the boom 5. The bracket 12 extends outwardly far enough to permit the swinging of the platform 4 with 35 relation to the frame and parts of the machine. A dipper 14 is carried by hangers 15 which are provided with the wheels 16 mounted between the flanges 17 of the I-beam or boom 11. The dipper is provided 40 with the usual points 18 and has a swinging bottom 19 which is preferably tripped from the rear of the dipper.

A driving or pull-out line 20 is operated from the drum 21 on the platform and extends 45 from a sheave 22 on the main boom 5 around a sheave 23 on the auxiliary boom, over a sheave 24 at the outer end of the auxiliary boom, around a sheave 25 on the dipper and is anchored preferably to the outer 50 end of the boom. Stops 26 are arranged on the dipper and engage buffer blocks 27 on the auxiliary boom.

The end of the dipper stick is secured to a bracket 28 on the auxiliary boom by means 55 of a pin 29.

In the operation of the device starting

with the parts as shown in the drawing the boom 11 is swung to the portion of the work desired to be operated upon by swinging the platform in the usual manner of steam shovels. The dipper is driven into the work by the pull-out line 20 which forces the dipper along the boom 11. The boom and in consequence the dipper is held to its work through the action of the dipper stick and 60 the crowding engine 7. When the dipper is filled it is carried to the end of the auxiliary boom 11 and the auxiliary boom is lifted through the action of the dipper stick and the dipper swung over the wagon or 65 other receptacle and dumped by dropping the bottom 19. The dipper is then permitted to run back on the boom by gravity and the auxiliary boom is lowered to the horizontal position and swung to the position of the 70 work and the operation is repeated.

It will be noted that this construction while giving a practically direct thrust to the dipper through the horizontal positioning of the boom also permits of a setting and 80 holding of the auxiliary boom to the work by means of the dipper stick. Further it makes applicable the ordinary steam shovel with very little change so that it forms merely an attachment for a steam shovel and 85 it also provides a mechanism which operates in a manner so nearly analogous to the ordinary steam shovel that an operator familiar with steam shovel practice has no difficulty in immediately operating the grader so 90 formed.

What I claim as new is:

1. In a grading machine, the combination of a platform; a boom pivotally mounted upon the platform and extending from the platform; a dipper having a cutting edge directed away from the platform and movable along the boom; a dipper stick actuating the boom to raise and lower the outer end of the boom; a crowding engine operating on the dipper stick; a mounting for the crowding engine; a drum on the platform; and a line extending from the drum to the dipper for actuating the dipper along the boom. 100

2. In a grading machine, the combination of a platform; a boom pivotally mounted upon the platform and extending from the platform; a dipper having a cutting edge directed away from the platform and movable along the boom; a dipper stick actuating the boom to raise and lower the 110

outer end of the boom; a crowding engine 5 operating on the dipper stick; a mounting for the crowding engine; a drum on the platform; and a line extending from the drum to the dipper by way of the end of the boom.

3. In a grading machine, the combination of a swinging platform; a boom pivotally mounted upon the platform and extending 10 from the platform; a dipper having a cutting edge directed away from the platform and movable along the boom; a dipper stick actuating the boom to raise and lower the outer end of the boom; a 15 crowding engine operating on the dipper stick; a mounting for the crowding engine; a drum on the platform; and a line extending from the drum to the dipper for actuating the dipper along the boom.

20 4. In a grading machine, the combination of a platform; a main boom extending from the platform; an auxiliary boom mounted below the main boom; a dipper movable along the auxiliary boom; a drum 25 on the platform; a line extending from the drum to the dipper; a dipper stick mounted on the main boom and secured to the auxiliary boom; and a crowding engine mounted on the main boom and acting on the dipper 30 stick.

5. In a grading machine, the combination of a platform; a main boom extending from the platform; an auxiliary boom mounted below the main boom; a dipper

movable along the auxiliary boom; a drum 35 on the platform; a line extending from the drum to the dipper by way of the end of the auxiliary boom; a dipper stick mounted on the main boom and secured to the auxiliary boom; and a crowding engine mounted 40 on the main boom and acting on the dipper stick.

6. In a grading machine, the combination of a swinging platform; a main boom extending from the platform; an auxiliary 45 boom mounted below the main boom; a dipper movable along the auxiliary boom; a drum on the platform; a line extending from the drum to the dipper; a dipper stick mounted on the main boom and secured to 50 the auxiliary boom; and a crowding engine mounted on the main boom and acting on the dipper stick.

7. In a grading machine, the combination of a platform; a main boom extending 55 from the platform; an auxiliary boom mounted below the main boom; a dipper movable along the auxiliary boom; a drum on the platform; a line extending from the drum to the dipper; a dipper stick mounted 60 on the main boom and secured to the auxiliary boom; a crowding engine mounted on the main boom and acting on the dipper stick; and pivotal mountings for said 65 booms, said mountings being adjacent.

In testimony whereof I have hereunto set my hand.

WILLIAM E. McCAIN.
